UNITED STATES PATENT OFFICE.

JOSEPH STAUDACHER, OF BUTLER, PENNSYLVANIA.

REFRIGERATOR.

No. 843,044.

Specification of Letters Patent.

Patented Feb. 5, 1907.

Application filed September 15, 1905. Serial No. 278,583.

To all whom it may concern:

Be it known that I, JOSEPH STAUDACHER, a citizen of the United States, residing at Butler, in the county of Butler and State of Pennsylvania, have invented certain new and useful Improvements in Refrigerators, of which the following is a specification.

My invention relates to refrigerators, and has for its object to provide a refrigerator adapted to utilize the low temperature of the ice drippings for lowering the temperature within the refrigerator.

With this and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a cross-section to my improved refrigerator on line 1 1 of Fig. 2. Fig. 2 is a cross-section through line 2 2 of Fig. 1. Fig. 3 is a horizontal cross-section through line 3 3 of Fig. 2. Fig. 4 is a top plan view of one of the drip-pans.

Referring to the drawings, in which like numerals of reference designate corresponding parts throughout the several views, 1 are the side walls, and 2 and 3 the top and bottom, respectively, of a refrigerator. An ice-chamber 4, located in the upper portion of the refrigerator, is provided with an air-passage 5 between the top 2 of the refrigerator and wall 5^a of the ice-chamber. A sheet of thin metal 21, preferably galvanized sheet-iron, arranged on one wall of the ice-chamber, as shown, serves to prevent contact of the ice with the said wall. The drip from the sheet 21 falls into a receptacle, herein-after referred to. On said wall 5^a passages 6 are formed by strips 7, secured thereto. The bottom 8 of said ice-chamber supports a pan 9, in which is placed a slatted bottom 10. Pan 9 is so disposed within the ice-chamber that a passage 11 is left between it and the end wall 1 to allow the cold air to pass from said chamber to the lower part of the refrigerator. Along the side of the pan farthest from air-passage 11 is formed an elongated spout 12, the outer edge of which extends to the side wall of the ice-chamber. It will be observed that the cold air is thus pre-

vented from passing from the ice-chamber to the space below, except through the passage 11 or spout 12. Drip-pans 14, provided with openings 15 in the bottom thereof and hooks 60 on their ends, are supported by eyes 17, secured to the sides of the refrigerator. The openings 15 have inserted in them short tubes 18, which reach nearly to the top of the pan, thereby preventing the water from escaping to the pan below until the first pan is nearly full. The overflow from each of these pans is caught by the pan below. The bottom pan has located beneath its opening a pipe 19 for conducting the water without the refrigerator. For convenience in cleaning the pans suitable valved outlets 20 are provided.

From the foregoing description it will be seen that the drippings from the melting ice 75 in chamber 4 will be caught by pan 9 and conducted through spout 12 to the first drip-pan 14. When the water in said drip-pan has reached the top of the tube 18, the overflow will pass through said tube into the drip-pan next below it, and so on through the series of drip-pans 14 until it is discharged by the lowest drip-pan in pipe 19, by which it is conducted without the refrigerator. By locating the outlet of each drip-pan at the end 80 opposite the drip-pan next above it the water has to travel the length of the pan before it is discharged therefrom. As the cold air from the ice-chamber 4 descends through passage 11 it sucks in the warm air through opening 5 from the opposite side of the refrigerator. This forms a current of air from one side of the refrigerator to the other, said air necessarily coming in contact with the pans of drip-water, which will tend to equalize the 90 temperature of said air and water. The current of air passing over the surface of the water will cause more or less evaporation, which will also reduce the temperature within the refrigerator. When it is desired to clean the 100 pans, they may be removed for that purpose.

Having thus described my invention, what I claim as novel, and desire to secure by Letters Patent, is—

In a refrigerator, the combination, with an 105 outer casing, of an interior compartment comprising a bottom and side walls and adapted to contain ice, the base of said compartment being provided with a single narrow or restricted opening, a series of narrow vertically-disposed receptacles arranged in proximity to each other and adapted to suc-

cessively receive the ice drippings from said compartment, said series of receptacles being arranged under said opening, hooks or lugs carried by each end of said receptacles and 5 hook-engaging supports carried by said walls and coacting with said hooks or lugs to form a positive support for said receptacles.

In testimony whereof I affix my signature in presence of two witnesses.

JOSEPH STAUDACHER.
